PAD HOLDER

Emanuel Gale, New York, N. Y.

Application March 13, 1941, Serial No. 383,129

8 Claims. (Cl. 281—19)

This invention relates to pad holders.

An object of this invention is to provide a pad holder having means to support a pad in such a way that the leaves thereof may be turned to the back, leaving a blank page in front ready for use.

A further object of this invention is to provide a pad holder of the character described in the form of a folder provided with a swinging arm on which the pad is adapted to be mounted, said arm being pivoted adjacent the fold of the folder and between the sides thereof, so that the pad may be swung relative to the sides of the folder, thus permitting free use of both sides of the folder, and also facilitating mounting of the pad on the swinging arm.

A still further object of this invention is to provide a pad holder of the character described having an arm pivoted to a link, which in turn is pivoted to the folder, the arm having means to removably grip the back of the pad for supporting the pad, said arm being adapted to be positioned in spaced, parallel relation to a side or wall of the folder, thus giving room for used pages which may be turned to the back of the pad and between said arm and said side of said folder.

Yet another object of this invention is to provide a pad holder of the character described in the form of a folder having an arm pivoted adjacent the fold of the folder and between the sides of the folder, and located adjacent the upper edge of the folder, said arm having means to engage the back of a pad of the type wherein the leaves are mounted on a wire coil or ring, so that the coil may be positioned outside of the folder, whereby as the number of pages or leaves of the pad decreases the bulk of the folder with the pad correspondingly decreasing.

Yet another object of this invention is to provide a pad holder of the character described, comprising a folder and means removably mounted thereon for detachably supporting a pad.

Yet a further object of this invention is to provide a durable and compact pad holder of the character described, which shall be easy to manipulate, inexpensive to manufacture, attractive in appearance, and yet practical and efficient to a high degree.

Other objects of this invention will in part be obvious and in part hereinafter pointed out.

The invention accordingly consists in the features of construction, combinations of elements, and arrangement of parts which will be exem-

plified in the construction hereinafter described, and of which the scope of application will be indicated in the following claims.

In the accompanying drawings, in which is shown various possible illustrative embodiments of this invention:

Fig. 1 is a perspective view of a pad holder embodying the invention;

Fig. 2 is a partial, front, elevational view thereof;

Fig. 3 is a cross-sectional view taken on line 3—3 of Fig. 2;

Fig. 4 is a cross-sectional view taken on line 4—4 of Fig. 2;

Fig. 5 is an enlarged, cross-sectional view taken on line 5—5 of Fig. 2;

Fig. 6 is a partial, cross-sectional view similar to Fig. 3, but showing the swinging arm flattened against a section of the folder;

Fig. 7 is a perspective view of the pad holder embodying the invention, and illustrating a modified construction;

Fig. 8 is a perspective view of another modified form of the invention; and

Fig. 9 is a cross-sectional view taken on line 9—9 of Fig. 7.

Referring now in detail to the drawings, 10 designates a pad holder embodying the invention. The same comprises a folder 11 made of leather, leatherette, paper, cardboard, or any other suitable material. The folder 11 comprises a pair of front and back sides, walls or sections 12 and 13 interconnected by a central fold portion 14. Any suitable pockets 12a and 13a may be stitched to the inner surfaces of sections 12 and 13. The sections 12 and 13 may be of substantially the same size.

Attached to the inner surface of section 13, adjacent the upper edge thereof, and adjacent the central fold 14, is a plate 17 having at the inner edge thereof, a rolled over bearing portion 19 parallel to said fold. Hinged to the bearing 19, is a link 20 having parallel, horizontal portions 21 and 22 interconnected by upper and lower end portions 23. Portion 21 is journalled in bearing 19, as shown in Fig. 4 of the drawings.

Hinged to portion 22 of the link 20 is an arm 25 on which a pad 26 is adapted to be detachably mounted in the manner hereinafter appearing. Arm 25 may be made of a single elongated strip of metal. The same comprises a straight portion 27, from one end of which there extends a bearing 28, rotatably receiving said portion 22 of the link. Extending from the bear-

ing 28 is a prong portion 29 parallel to portion 27. Extending from the opposite end of portion 27 is a bent back prong portion 30, symmetrical to prong portion 29. Prong portions 29 and 30 are parallel to portion 27.

The length of arm 25 is substantially equal to the width of section 13, so that the arm does not project beyond said section. It will now be understood that the arm 25 may swing about the link 20.

The pad 26 mounted on arm 25 is of the type generally known as "spiral" pads. The same comprises a cardboard, substantially stiff back member 36, and a plurality of leaves 37, said back member and the leaves being formed with registering openings 38, receiving a helical wire coil 40 which binds the sheets and backing member together.

The back member 36 is inserted between prong portions 29 and 30 and portion 27, as illustrated in the drawings, being frictionally gripped therebetween. The coil 40 is preferably disposed above the upper edges of sections 12 and 13. The leaves 37 of the pad 26 lie on top of portion 27.

When the folder is open, the leaves 37 are presented. The leaves 37 after being used may be swung over through an angle of 360 degrees, around to the back of arm 25.

It will be noted that arm 25 may be positioned in spaced parallel relation to section 13, giving room for the turned back sheets or leaves. When there are no turned back leaves, arm 25 may be swung to the position shown in Fig. 6, against section 13 of the folder. As the leaves are turned back between the back member 36 and section 13, the arm 25 will naturally move away from said section, said link being thereby caused to swing from the position shown in Fig. 6 to the position shown in Fig. 3, where it is perpendicular to section 13.

It will be noted that prongs 29 and 30 are located between portion 27 and section 13, room for the prongs being provided because of the link 20. If desired, however, the prongs may be formed on the front of arm 25 instead of on the back thereof.

It will be noted that the pad may be removed by merely pulling the back upwardly until it is disengaged from arm 25. With the present construction, it is possible to save notes. The sheets which need not be saved may be torn off, and the sheets it is desired to save, may be swung around to the back of the pad.

Since arm 25 with the pad thereon may be swung about its hinge, the pockets 12a and 13a are accessible for use. Furthermore the insertion of the pad is facilitated by swinging the arm away from section 13. The arm 25 is located near the upper edge of section 13, so as not to make the folder too bulky.

In Fig. 7 there is shown a pad holder 10a embodying a modified form of the invention. The same comprises a folder 11a, similar to the folder 11, and attached to the inner surface of one of its sections, is a plate 58, to which there is hinged a link 51. Hinged to the link 51 is an arm 52, on which the pad 26 is detachably mounted in a manner hereinafter appearing.

Arm 52 is made of a single strip of spring metal and comprises superimposed portions 54 and 55 interconnected by a bearing portion 56 rotatably mounted on the link.

The outer end of portion 55 may be bent, as at 57, toward portion 54, said bent portion extending beyond the outer end of said portion 54. The

back 36 of the pad may be inserted between portions 54 and 55, and is frictionally held therebetween. Said back may be inserted by pushing the same between portions 54 and 55. The bent over portion 57 prevents the back from slipping out of arm 52.

In Figs. 8 and 9 there is shown a pad holder 10b embodying another modified form of the invention. The pad holder 10b comprises a folder 60 having sections 61 and 62. Stitched to section 62 is an elongated pocket 63, open at its inner end, as at 64, adjacent the fold 65 between the sections 61 and 62.

Inserted into the pocket 63 is a tongue 68 having a bearing portion 69 at one end located outside of the pocket. Hinged to the bearing 69 is a link 70, and hinged to said link is an arm 71 having a pair of prongs 72 cut from said arm and pressed forwardly into spaced parallel relation to the body of said arm. Back 36 of the pad may be inserted between the prongs 72 and the body of the arms 71.

If desired, the arm 71 with its link 70, and tongues 68, may be removed from the folder 60.

It will thus be seen that there is provided a device in which the several objects of this invention are achieved, and which is well adapted to meet the conditions of practical use.

As various possible embodiments might be made of the above invention, and as various changes might be made in the embodiments above set forth, it is to be understood that all matter herein set forth or shown in the accompanying drawings is to be interpreted as illustrative and not in a limiting sense.

Having thus described my invention, I claim as new and desire to secure by Letters Patent:

1. In combination, a folder having front and back sections interconnected by a fold portion, a link pivoted to the inside of the folder about an axis parallel to and adjacent the fold portion, and an arm pivoted to said link about an axis parallel to the first axis, and likewise disposed adjacent said fold portion, said arm being disposed adjacent the upper edge of the folder and adapted to swing from the front section to the back section thereof, and said arm being located substantially wholly between the front and back sections of said folder, said arm having means to support a pad mounted thereon and located between the front and back sections of the folder, and swingable with said arm from the back to the front sections.

2. In combination, a folder having front and back sections interconnected by a flexible fold portion, a hinge member attached to one of said sections and formed with a hinge bearing located adjacent the fold portion, the axis of said bearing being parallel to and closely adjacent to said fold portion, a link having parallel interconnected arms, one arm being journalled in said hinge bearing, a member made of a single piece of strip metal formed with a bearing at one end receiving the other arm of said link, said member having parallel portions forming a groove therebetween to frictionally receive the back of a pad mounted on said member.

3. In combination, a folder having front and back sections interconnected by a flexible fold portion, a hinge member attached to one of said sections and formed with a hinge bearing located adjacent the fold portion, the axis of said bearing being parallel to and closely adjacent to said fold portion, a link having parallel interconnected arms, one arm being journalled in said

hinge bearing, a member made of a single piece of strip metal formed with a bearing at one end receiving the other arm of said link, said member having parallel portions forming a groove therebetween to frictionally receive the back of a pad mounted on said member, said member being wholly located between said sections and adjacent the upper end of said folder.

4. In combination, a folder having front and back sections interconnected by a flexible fold portion, a hinge member attached to one of said sections and formed with a hinge bearing located adjacent the fold portion, the axis of said bearing being parallel to and closely adjacent to said fold portion, a link having parallel interconnected arms, one arm being journaled in said hinge bearing, a member made of a single piece of strip metal formed with a bearing at one end receiving the other arm of said link, said member having parallel portions forming a groove therebetween to frictionally receive the back of a pad mounted on said member, said member being wholly located between said sections and adjacent the upper end of said folder, one of said parallel portions of said member having a curved lip at the end thereof overlying the outer end of the other parallel portion of said member to retain the back of the pad against slipping out sideways from said member.

5. A folder comprising a front section and a back section interconnected by a flexible fold portion, a pocket stitched to the inside of one of said sections, said pocket being open at the end thereof adjacent the fold portion, a plate inserted into said pocket and formed with a bearing disposed outside of the pocket, said bearing having an axis parallel to the fold portion and disposed adjacent to said fold portion, a link hinged to said bearing, and an arm hinged to said link about an axis parallel to said bearing, said arm having parallel portions adapted to receive the back of a pad therebetween.

6. A folder comprising a front section and a back section interconnected by a flexible fold portion, a pocket stitched to the inside of one of said sections, said pocket being open at the end there-

of adjacent the fold portion, a plate inserted into said pocket and formed with a bearing disposed outside of the pocket, said bearing having an axis parallel to the fold portion and disposed adjacent to said fold portion, a link hinged to said bearing, and an arm hinged to said link about an axis parallel to said bearing, said arm having parallel portions adapted to receive the back of a pad therebetween, said arm being located wholly within said sections and adjacent the upper end of said fold.

7. In combination, a folder having front and back sections interconnected by a flexible fold portion, hinge means at the inside of the folder and adjacent the fold portion, including an element disposed longitudinally of said fold portion, and disposed adjacent to said fold portion, and an arm rotatably mounted on said element, and adapted to be swung about said element from the back section to the front section, said arm being located between said back and front sections, and said arm having parallel portions to frictionally and removably receive therebetween a back of a pad disposed between the back and front sections of said folder and swingable with said arm from the back section to the front section.

8. In combination, a folder having front and back sections interconnected by a flexible fold portion, hinge means at the inside of the folder and adjacent the fold portion, including an element disposed longitudinally of said fold portion, and disposed adjacent to said fold portion, and an arm rotatably mounted on said element, and adapted to be swung about said element from the back section to the front section, said arm being located between said back and front sections, and means on said arm to removably support a pad disposed between the back and front sections of said folder and swingable with said arm from the back section to the front section, said arm being located between said back and front sections, and means on said arm to removably support a pad disposed between the back and front sections of said folder and swingable with said arm from the back section to the front section, said arm comprising a single piece of strip metal formed with a bearing at one end to rotatably receive said element, and having parallel portions adapted to frictionally receive therebetween the back of the pad supported on said arm.

EMANUEL GALE.
